US00D656153S

(12) **United States Design Patent**
Imamura et al.

(10) **Patent No.:** US D656,153 S
(45) **Date of Patent:** ** Mar. 20, 2012

(54) **COMPUTER DISPLAY WITH GRAPHICAL
USER INTERFACE**

(75) Inventors: **Ken Imamura**, Funabashi (JP); **Daisuke Kaguchi**, Hatano (JP); **Yutaka Tawara**, Hatano (JP); **Yoshinori Wakai**, Hatano (JP); **Eitaro Ito**, Kokubunji (JP); **Daisuke Nogami**, Musashino (JP); **Yuki Furuyama**, Kawasaki (JP); **Toshiyuki Moriwake**, Yokohama (JP); **Shinya Honda**, Yokohama (JP); **Junko Suzuki**, Tama (JP)

(73) Assignee: **Hitachi, Ltd.**, Tokyo (JP)

(**) Term: **14 Years**

(21) Appl. No.: **29/377,958**

(22) Filed: **Oct. 28, 2010**

(30) **Foreign Application Priority Data**

Jul. 9, 2010 (JP) 2010-016837

(51) **LOC (9) Cl.** **14-04**

(52) **U.S. Cl.** **D14/486**

(58) **Field of Classification Search** D14/485, D14/486, 487, 488, 489, 490, 491, 492, 493, D14/494, 495; 345/426, 594, 902; 715/700, 715/703, 715, 716, 719, 720, 727, 728, 758, 715/762, 763, 768, 773, 779, 780, 781, 790, 715/808, 809, 810, 828, 835, 840, 841, 842, 715/843, 864, 867, 961, 962, 963, 966, 975

(57) **CLAIM**

We claim the ornamental design for a computer display with graphical user interface, as shown and described.

DESCRIPTION

The single FIGURE is a front elevational view of a computer display with graphical user interface showing our new design. The broken line drawing of a computer display in the FIGURE is for illustrative purpose only and forms no part of the claimed design.
